SEWING MACHINE

Frederick F. Zeier, Stratfield, Conn., assignor to
 The Singer Manufacturing Company, Elizabeth, N. J., a corporation of New Jersey

Application November 19, 1945, Serial No. 629,362

18 Claims. (Cl. 112—235)

1

This invention relates to sewing machines and, more particularly, to sewing machines having upper four-motion feeding mechanisms, and for automatic presser-foot lifting mechanisms.

In an upper four-motion feeding mechanism of the character known as the alternating presser type, there is employed an automatic presser and feeding-foot lifting mechanism which is normally dependent upon the resistance imposed by the work or its support to the downward movement of either the presser-foot or feeding-foot, in order to provide a fulcrum for lifting the other of said members. Therefore, if any inertia or cramping of the parts occasions a sufficient resistance before either of said members in its descending movement reaches the work, the necessary fulcrum will be untimely provided and neither of said members will engage the work with the requisite pressure to insure a proper work-feeding action. The liability of imperfect operation of prior feeding mechanisms of this character increases with the speed of operation of the machine, due in a large measure to inertia of the parts and also because the spring which depresses the presser and feeding foot elements cannot recover with sufficient rapidity to overcome the upward movements thereof. At high speeds a degree of inefficiency may be reached wherein neither the presser-foot nor the feeding-foot perceptibly engages the work.

It is therefore, an object of this invention to provide, in a machine of this type, improved feeding and presser-foot lifting mechanism which will enable the machine to be operated at a much higher rate of speed than heretofore was possible.

A further object of the invention is to provide a machine of the present type with feeding and presser mechanisms so designed that there will be no tendency for the presser-foot and the feed-foot to flutter above the throat-plate whenever the machine is operated at a high rate of speed.

Another object of this invention is to provide an improved mechanism for imparting work-feeding movements to the needle-bar and upper feed-bar elements.

Still another object of this invention is to provide means whereby the violent vibrations which are set up in the presser-bar spring may be properly absorbed.

With the above and other objects in view, as will hereinafter appear, the invention comprises the devices, combinations, and arrangements of parts hereinafter set forth and illustrated in the accompanying drawings of a preferred embodiment of the invention, from which the several

2

features of the invention and the advantages attained thereby will be readily understood by those skilled in the art.

Fig. 1 represents a rear side elevation of a sewing machine in which the present invention is incorporated.

Fig. 2 represents a left side elevation of the sewing machine showing the stitching and feeding mechanisms with the bed and work-supporting plate in section, and with the needle in its uppermost position.

Fig. 3 represents a left side elevation of the stitching and feeding mechanisms as removed from the sewing machine frame and with the needle in its lowermost position.

Fig. 4 is a detail view, in elevation, of the feed-lift crank in its raised or inoperative position, with the lock-pin device sustaining the crank in this position.

Fig. 5 is a diagrammatic illustration of the stitching and feeding mechanisms shown in Fig. 2, with the top feeding foot in raised position.

Fig. 6 is a diagrammatic illustration of the stitching and feeding mechanisms shown in Fig. 2 with the alternating presser-foot in raised position.

Fig. 7 represents a sectional view illustrating the needle-bar oscillating mechanism; the section being taken substantially along line 7—7 of Fig. 1.

Fig. 8 represents a sectional elevation of the presser spring and its vibration-damping cylinder.

Fig. 9 represents a top plan view of the connecting means between the damping cylinder and its carrying arm.

Fig. 10 represents a sectional view of the upper feeding and stitching mechanism taken substantially along line 10—10 of Fig. 1.

Fig. 11 represents a sectional view of a portion of the feed- and presser-bar actuating mechanism taken substantially along line 11—11 of Fig. 2.

Fig. 12 represents a sectional view showing a portion of the presser-bar with its associated elements and taken substantially along line 12—12 of Fig. 10.

Fig. 13 represents a sectional view showing a portion of the presser- and feed-bar lifting means and taken substantially along line 13—13 of Fig. 10.

Referring to the drawings, the invention is embodied in a sewing machine having a frame comprising a bed 11 from one end of which rises a standard 12 of an overhanging bracket-arm 13 terminating in a head 14. Journalized for rotation

within this frame is a main- or arm-shaft 15 carrying at its outer end the usual belt-driven balance-wheel 16 and at its inner end a counterbalanced needle-bar actuating crank 17. Shaft 15 is connected by a clip-belt 18, herein shown incompletely, to a belt-pulley 19 fast upon the outer end of a lower main- or bed-shaft 20 journaled for rotation in the bed 11, the ratio between the shafts 15 and 20 being one-to-one.

Actuated by the bed-shaft 20 is the usual lower four-motion work-feeding mechanism, including a feed-dog 21, and the looper mechanism including a threaded chain-stitch looper 22. For the sake of brevity, a detailed description of the four-motion feeding mechanism will not be given herein, inasmuch as the same is fully described and claimed in my U. S. Patent No. 2,292,258, Aug. 4, 1942.

With regard to the looper mechanism disclosed in the drawings, it will suffice to say that the looper 22 is preferably of the two-motion type having loop-seizing and -shedding movements only in the line of feed, the looper advancing to seize the needle-loop in a direction opposed to the direction of feed.

Referring now to the mechanism within the machine-head 14, it will be seen in Figs. 3 and 7 that a needle-bar actuating link 23 is pivotally mounted upon the crank 17 by means of a screw 24. The lower end of the link 23 is apertured to receive a pin 25 integral with a split collar 26 clamped upon the usual needle-bar 27. Carried at the lower end of the needle-bar 27 is a suitable needle 28. Through the mechanism just described the needle-bar 27 is reciprocated endwise in proper timed relation with the complementary looper 22 to produce chain-strokes.

The needle-bar 27 is journaled in bearing members 29 and 30 projecting from the needle-bar frame 31 which is provided with a horizontally projecting fulcrum-rod 32 journaled within the lug 33 of the machine head 14.

The needle-bar-frame 31, in the machine illustrated, is oscillated in timed relation with the four-motion feed-dog 21 through mechanism comprising a rock-lever 34 preferably clamped at its lower end by screws 35 upon the end portion of the fulcrum-rod 32. At its upper end, the rock-lever 34 is pivotally connected, by means of a bolt 36 and a nut 36', to one end of a relatively short pitman 37 formed at its other end with a strap 38 embracing the adjustable eccentric 39 secured to rotate with the arm-shaft 15. It will be understood that as the arm-shaft 15 is rotated, the eccentric 39 actuates the pitman 37 which in turn operates the rock-lever 34 to oscillate the needle-bar frame 31 about the axis of the fulcrum-rod 32. The extent of oscillatory movement imparted to the needle-bar frame is dependent upon the amount of eccentricity of the eccentric 39 and, in order to vary the amplitude of the oscillatory movements of the needle-bar frame to harmonize with the stitch-length to which the lower feeding mechanism is set, the eccentric 39 is made adjustable. A complete description of this type of adjustable eccentric may be found in the U. S. patent of W. Myers, No. 2,128,031, Aug. 23, 1938.

To effect adjustment of the eccentric 39 the top of the bracket-arm 13 has mounted therein a detent 40, the details of construction of which are similar to those illustrated in the U. S. patent of W. Myers, No. 2,063,264, Dec. 8, 1936. When it is desired to adjust the amplitude of oscillation of the needle-bar frame 31, the detent

40 is depressed until the inner end 41 thereof enters a stop-notch 42 in the adjusting-member 43 of the eccentric 39, after which if desired the detent can be partly rotated and locked in depressed position. With the adjusting-member 43 of the eccentric 39 thus latched against turning, suitable manual turning of the arm-shaft 15 will effect the desired adjustment of the eccentric 39.

For a more detailed description of the present type of needle-bar mechanism reference may be had to my U. S. Patent No. 2,329,681, Sept. 14, 1943.

Referring particularly to Figs. 2 and 3, it will be seen that the needle-bar frame 31 has a vertically apertured bearing lug 44 formed thereon adjacent the bearing portion 30. Slidably mounted within this bearing lug 44 is a top-feed-bar 45 carrying at its lower end a feeding foot 46 which is adapted to cooperate with the needle 28 and the lower feed-dog 21 in the feeding of the work over the bed-plate 47. Since the feed-bar 45 is carried by the needle-bar frame 31, the latter element will impart the same amplitude of vibrating motion in the line of feed to both the needle-bar 27 and the top feed-bar 45.

The upper end of the top feed-bar 45 is provided with a cross-pin 48 which is slidably received within the forked free end 49 of a substantially horizontally disposed feed-lift lever 50. The confined end of the lever 50 is pivotally mounted upon a pin 51 which is carried within the lower rear portion of the machine head 14.

In order to prevent the feed-bar 45 from turning about its longitudinal axis, the top portion thereof is provided with a pair of checks 45' which carry the cross-pin 48 and which embrace the forked portion 49 of the lever 50.

The machine head 14 is provided with a vertically disposed stationary bearing member 52 in which a presser-bar 53 is slidably mounted so as to be located slightly rearwardly of the top feed-bar 45 and out of the line of feed at that side of the line of feed nearest to the machine bracket-arm 13. A usual type of presser-foot 54 is carried by the lower end of this presser-bar 53. Formed in the upper portion and between the ends of the presser-bar 53 is a slot 55, Fig. 12, which is adapted to receive the free end of one arm 56 of a bell-crank lever which is pivotally carried by and at the center of percussion of the feed-lift lever 50.

This bell-crank lever comprises the above noted arm 56 carried by one end of the pivot pin 57 upon the other end of which is secured, by means of a screw 58, a second arm 59 which is pivotally connected by a pin 60 to the lower end of a link 61. The pin 57 passes through the apertured bearing portion 62 of the lever 50 whose center of percussion lies along the axis of bearing portion 62.

The upper end portion of the link 61 is connected by means of a pin 63 to an actuating crank 64 carried by one end of a rock-shaft 65 which is journaled in bearing lugs 66 and 67 provided on the machine bracket-arm 13 and head 14 respectively. The rock-shaft 65 is disposed in parallelism with the needle-bar actuating shaft 15.

Secured upon the opposite end portion of the rock-shaft 65, by means of screws 68, is a short crank 69 carrying a pin 70 which is pivotally embraced by the forked end of a pitman 71 whose other end terminates in an eccentric strap 72. Strap 72 embraces an adjustable eccentric 73 secured to rotate with the arm-shaft 15. It will be understood that as the arm-shaft 15 is rotated, the eccentric 73 actuates the pitman 71 which in turn

imparts rocking movements to the rock-shaft 65 through the medium of the crank 69. The amplitude of these movements may be varied by adjusting the throw of the adjustable eccentric 73. For a more complete description of an adjustable eccentric of this type, reference may be had to the U. S. patent of A. H. De Voe, Re. No. 14,218, reissued Nov. 28, 1916.

Pressing downwardly upon the feed-lift lever 50, at a point between the bell-crank pivot-point and the forked end 49 thereof, is one end of a spring-biased blade-lever 74 which is located outside of and rearwardly adjacent to the machine bracket-arm 13. The other end of this lever is biased upwardly by means of a coil spring 75 which is operatively connected to an arm 76 mounted upon the bracket-arm 13. The lower end of the spring 75 is pivotally connected to the lever 74 by means of a bolt 77 and nut 78. As illustrated more particularly in Figs. 10 and 13, the lever 74 is fulcrumed adjacent to the feed-lift crank 50 upon a knife-edge 79' of a fulcrum-piece 79 extending from a stub-shaft 80 which is rockably mounted within an aperture 81 formed in the lower portion of the machine head 14. In order to prevent the spring-biased lever from exerting any side thrust upon the feed-lift lever 50, a steel ball 82 is held, by means of a sheet metal cage 83, between said lever 74 and lever 50. The cage 83 is secured to the lever 50 by means of screws 84.

Referring particularly to Figs. 10 and 13, it will be seen that the lever 74 is apertured so as to afford clearance for a guide-pin 85 projecting upwardly from the shelf portion 86 of the head 14 and extending through the forked end of a guide-arm 87 which is clamped by means of a screw 88 to the upper reduced portion of the presser-bar 53. Thus the presser-bar 53 is prevented from turning about its longitudinal axis and at the same time the pin 85 prevents the lever 74 from moving sidewise.

The oscillatory motions of the above noted rock shaft 65 cause the bell-crank lever 56, 59 to swing in a vertical plane about its pivot pin 57 in the feed-lift lever 50, so that the arm 56 thereof successively tends to lift and depress the presser-bar 53. When the presser-bar 53 is depressed, however, its presser-foot 54 engages the throat-plate 89, or the work carried thereby, and further movement of the bell-crank lever can only result in raising the pivot point thereof, which latter action will, of course, raise the forked end 49 of the feed-lift lever 50 with the consequence that the top feeding-foot 46 is lifted clear of the throat-plate 88, as is illustrated in Figs. 2 and 5. Continuous oscillation of the rock-shaft 65 will, therefore, cause the presser-bar 53 and the top feed-bar 45 alternately to rise and fall, and the spring-biased lever 74 being in continuous engagement with the feed-lift lever 50, it will have its force transmitted to either the presser-bar or to the top feed-bar, depending upon which one of the two elements is in engagement with the throat-plate or work. The motions of the rock-shaft 65 are synchronized with those of the needle-bar 27 so that the usual compound feeding motions will be effected.

Adjustment of the rock-shaft actuating eccentric 73 will effect a relative adjustment in the amplitude of the vertical movements imparted to the presser-bar and top feed-bar.

The feed-lift lever 50 and the actuating crank 64 are each counterbalanced as at 90 and 91, Fig. 2, to permit high speed operation of the machine.

As hereinabove noted, one end of the lever 74 is pivotally secured to the coil spring 75 by means of the bolt 77. Referring more specifically to Figs. 1, 8 and 9, it will be seen that the lower end of the spring 75 is secured to the lower cup-shaped member 92 which is telescopically fitted within the upper and reversely directed cup-shaped member 93 whose upper portion has a threaded rod 94 projecting upwardly therefrom. This rod is received within and clamped by a split collar 95 having a threaded bolt portion 96 extending therefrom to be pivotally received by the arm 76 and secured thereto by means of nuts 97. The upper end of the spring is secured to the member 93, thus to bias the lever 74 upwardly. The two cup-shaped members 92 and 93 form a substantially airtight unit whose purpose is to dampen the violent spring vibrations which would otherwise occur when the spring 75 passes through its critical phases. A rubber spacer 75' is disposed within the spring to limit lateral vibration thereof.

The applied pressure of the spring 75 may be varied by shifting the rod 94 relative to the clamp collar 95. The shifting of the rod 94 relative to the collar 95 is effected by turning a tension-adjusting nut 98, which is threaded upon the rod 94.

Referring particularly to Fig. 1, the fulcrum point 79' of the spring-biased lever 74 is so located that the lever is of the first class; the portion thereof extending forwardly of the fulcrum point 79' being materially shorter in length than that portion which extends from the lever pivot point at 77 to the fulcrum point at 79'. By means of the lever, or multiplying means 74, the amplitude of vertical movement of the feed-lift lever 50 is, in a preferred form of the device, multiplied by five at the end of the lever 74, thus to impart to the crank a force five times greater than the spring would impart thereto if it were acting directly upon the crank. Thus a relatively light spring is adequate for supplying the proper pressure to the presser-foot and top feeding foot. Tests have proven that by using such a multiplier, superior results have been attained, as compared to the results attained when using the same top feeding and presser elements but with a spring having about five times the stiffness of spring 75 and applied to bear directly upon the lever 50. Apparently there is much advantage to be gained by using a lightweight spring coupled with a "multiplier" as compared to using a heavier weight spring which is applied directly upon the lever 50. These tests have shown that the use of the present multiplier mechanism completely obviates the tendency of the feet 46 and 54 to flutter when the machine is operating at a high rate of speed. It is an advantage to use a spring having a high natural frequency for uses of this kind.

The present machine is also provided with manually operable presser- and top feed-bar lifting means designed to keep at a minimum the lifting force required. Broadly, these means comprise elements adapted, under treadle-controlled action, to remove completely the coil spring tension on arm 74 and to swing the knife-edge fulcrum 79 of the spring-biased lever 74 away from said lever to permit the presser- and feed-bars freely to be raised off the work. This mechanism forms the subject of a separate patent application.

In general, the present lifting mechanism com-

prises a self-contained frame-work 99 carried by the machine bracket-arm 13. Within this frame-work 99, are mounted two sets of Geneva stops 100 and 101 geared together in order to provide a series of successive motions all produced by a single downward movement of the usual foot-actuated treadle which is connected to the Geneva stops by means of a chain 102 and a pivoted arm 103, which latter carries a segment-gear 104. Responsive to an initial movement of the treadle-chain 102, through the connecting means of the segment-gear 104 and a pinion 105 engaged thereby, the primary Geneva stop 100 raises an arm 106 which actuates a toggle-joint comprising arms 107 and 108 pivotally connected as at 109. Arm 107 is pivotally carried by the frame-work 99 as at 110 and the other arm 108 of the toggle joint is pivotally connected as at 111 to an arm 112 which in turn is pivotally carried by the frame-work as at 113. The hereinabove noted arm 76 is integral with arm 112 and therewith forms a bell-crank lever which, under the action of the toggle joint, swings about its pivot 113 for the purpose of relaxing the coil spring 75.

At this point in the cycle, the spring pressure is entirely removed from the presser-bar and top feed-bar. Further downward movement of the treadle chain 102 will not move the bell-crank and coil spring 75 due to the inherent lost-motion action of the Geneva stop 100, but the second Geneva stop 101 then becomes effective to actuate a segment gear 114 which in turn imparts a forward linear motion to a horizontally disposed rack-bar 115 slidably mounted within the frame-work 99 and within a bearing aperture 116 formed in the head 14.

The forward end portion of this rack 115 engages gear teeth 117 provided on the end portion of the above noted stub-shaft 80 which carries the knife-edge 79 and, therefore, the linear movement imparted to the rack is effective to rotate the stub-shaft, thereby to remove the fulcrum point from the spring-biased lever 74 for the purpose of providing proper clearance between the lever 74 and the fulcrum so the lever 50 may be freely raised.

Threaded into the fulcrum-piece 79 of the stub-shaft 80, at a point eccentric to the axis of rotation thereof, is a screw 118 of which an exposed shoulder portion 119 enters a slot 120 provided adjacent one end portion of a sheet metal arm 121, the other end of which arm is pivotally secured to the under body of the machine bracket-arm 13 by means of a screw 122. The free end of the arm 121, adjacent the slotted portion thereof, is bent to form a lip 123 and underlies the guide-arm 87 carried by the presser-bar 53. The turning motion of the stub-shaft, therefore, throws the screw 118 in an arcuate path, thereby raising the free end portion of the sheet metal arm 121 which in turn lifts the presser-bar 53. This upward movement of the presser-bar lifts the top feed-bar 45 also through the medium of the bell-crank lever 56, 59 which is pivotally carried by the feed-lift lever 50.

Upon releasing the manually applied force exerted on the treadle chain 102, the above described mechanism will return to its normal position under the force of a tension spring 124 which is effective to retension the coil spring 75, as the spring 124 operates through the medium of the toggle joint.

The presser-bar and top feed-bar may be locked in their respective raised positions by

means of a vertically disposed lock-pin mounted in a lug 125 provided on the machine head 14. This lock-pin device comprises a hollow stationary sleeve 126 fitted into the lug 125 and secured therein by means of a set screw 127. Slidably mounted within the sleeve 126 is a cylindrical pin 128 having a slab-sided upper portion 129 which enters a corresponding slot 130 provided within the upper portion of the sleeve 126. This pin 128 is adapted to be raised manually against the force of a small coil spring 131 and then turned so that the slab-sided portion 129 of the pin is out of phase relative to the slot 130, which latter action is effective to lock the pin in its raised position as shown in Fig. 4. As the pin is located beneath the top feed-lift lever 50 it is effective, in its raised position, to prevent the lever, and consequently the presser-bar and top feed-bar, from returning to their normal lowered position.

From the foregoing description it is to be understood that the lever 74 functions to impose upon the spring 75 a range of movement materially greater than that of either the presser-bar or feed-bar. From this it will be understood that for every increment of upward movement made by either the presser- or feed-bar, there is applied thereto a quantum of spring-applied force which is greatly in excess of that which would be applied thereto if the spring were connected directly to the arm 50. Thus it is possible to use a relatively lightweight spring and still have available the requisite amount of spring pressure for efficiently biasing the work-engaging elements toward the work.

Furthermore, by employing the present pneumatic damping means in conjunction with the coil spring, it has been found that the violent vibrations which are set up in the spring as it passes through the critical phases are completely obviated.

Having thus set forth the nature of the invention, what I claim herein is:

1. In a sewing machine having a frame including a head and a work-support, the combination of a presser-bar slidably mounted upon said head, a coil-spring for pressing said presser-bar toward said work-support, and a relatively stiff lever of the first order having one end thereof operatively connected to said presser-bar and the other end thereof operatively connected to said coil-spring, said lever being adapted to impose upon said spring a range of movement materially longer than that of said presser-bar.
2. In a sewing machine having a frame including a head and a work-support, the combination of a presser-bar slidably mounted upon said head, a spring for biasing said presser-bar toward said work-support, means interposed in operative relation between said spring and said presser-bar for multiplying the applied force of said spring and applying the resultant upon said presser-bar, and means associated with said spring for damping excessive vibrations set up therein.
3. In a sewing machine, the combination of a work-engaging foot, a spring for biasing said foot toward the work, means interposed in operative relation between said spring and said foot for multiplying the applied force of said spring and applying the resultant upon said work-engaging foot, and pneumatic means associated with said spring for damping any vibrations set up therein.
4. In a sewing machine the combination of a work-engaging foot, a spring for biasing said

foot toward the work, means interposed in operative relation between said spring and said foot for multiplying the applied force of said spring and applying the resultant upon said foot, and pneumatic means associated with said spring for damping any vibrations set up therein, said pneumatic means comprising a cylinder having a pair of relatively movable members, said members being adapted to vary the air pressure within said cylinder in response to movements of said spring thereby to dampen the spring vibrations.

5. In a sewing machine, the combination of a presser-foot, a tensioned spring for biasing said foot toward the work, and pneumatic means associated with said spring for absorbing excessive vibrations which may be set up therein, said pneumatic means comprising, a substantially airtight cylinder formed of a pair of telescopically arranged members maintained in such relation by said tensioned spring, said members being adapted for movement relative to each other in response to movements of said spring thereby to dampen the spring vibrations.

6. In a sewing machine having a frame including a head, the combination of a presser-bar, a pair of telescopic arranged members forming a substantially airtight cylinder, one of said members being secured to said head and the other of said members being operatively connected with said presser-bar so as to be actuated thereby in response to all longitudinal movements of said presser-bar, and a coil-spring disposed within said cylinder with each end portion thereof secured to a respective one of said members, said coil spring when tensioned being effective to bias said presser-bar toward the work.

7. In a sewing machine having a frame including a head, the combination of a presser-bar slidably mounted within said head, a pair of telescopically arranged members forming a substantially airtight cylinder, a coil-spring disposed within said cylinder with each end portion thereof secured to a respective one of said members, one of said members being secured upon said head, and means operatively connecting the other of said members with said presser-bar so as to bias the presser-bar toward the work, said means comprising a motion-multiplying member adapted to impose upon said spring a range of movement materially longer than that of said presser-bar.

8. In a sewing machine, the combination of a plurality of work-engaging feet, a spring for pressing said feet upon the work, means interposed in operative relation between said spring and said feet whereby said spring is given a range of movement materially longer than that of either of said feet, and means for imparting mutually alternating lifting movements to said feet against the force of said spring.

9. The combination in a sewing machine having a frame including a work-support, a reciprocating presser-foot carrying bar, a feeding-foot carrying bar mounted for endwise reciprocating and laterally jogging work-feeding movements, means for reciprocally actuating said bars in directions toward and from said work-support, a spring for biasing each of said bars toward said work-support, and means interposed between said spring and each of said bars for multiplying the applied force of said spring and applying the resultant upon each bar.

10. The combination in a sewing machine having a frame including a work-support, a reciprocating presser-foot carrying bar, a feeding-foot

carrying bar mounted for endwise reciprocating and laterally jogging work-feeding movements, means for reciprocally actuating said bars in directions toward and from said work-support, a spring for biasing each of said bars toward said work-support, and means interposed between said spring and each of said bars for multiplying the applied force of said spring and applying the resultant upon each bar, said means comprising a lever of the first order having one end thereof associated with said spring and the other end thereof associated with said bars.

11. The combination in a sewing machine having a frame including a work-support, a reciprocating presser-foot carrying bar, a feeding-foot carrying bar mounted for endwise reciprocating and laterally jogging work-feeding movements, means for reciprocally actuating said bars in directions toward and from said work-support, a spring for biasing each of said bars toward said work-support, means interposed between said spring and each of said bars for imposing upon said spring a range of movement materially longer than that of either of said feet, and means associated with said spring for damping all excessive vibrations set up therein.

12. In a sewing machine, the combination of a work-engaging foot, a swinging arm, a pivotal support for said arm, a connection between said arm and said foot, a spring for pressing said foot upon the work, means connecting said spring with said arm, said means comprising a lever of the first order adapted to impose upon said spring a range of movement materially longer than that of said foot, and intermittently operable lifting means connected with said arm for lifting said foot against the force of said spring.

13. In a sewing machine, the combination of a plurality of work-engaging feet, a swinging arm, a pivotal support for said arm, an operable connection between said arm and one of said feet, a rocking member fulcrumed upon said arm intermediate its connection with said foot and its pivotal support, a connection between the other of said feet and said rocking member, means for actuating said rocking member, a spring for pressing said feet upon the work, and means connecting said spring with said arm, said last mentioned means comprising a lever of the first order adapted to impose upon said spring a range of movement materially longer than that of either of said feet.

14. In a sewing machine, the combination of a plurality of work-engaging feet, a swinging arm, a pivotal support for said arm, independent connections between said arm and said feet, lifting means connected with said arm, a lever having one end thereof connected with said arm, a spring connected to the other end of said lever so as to force said feet against the work, and a fulcrum member cooperatively associated with said lever and in engagement therewith at a point adjacent the arm so as to provide the spring with a range of movement materially longer than that of either of said feet.

15. In a sewing machine having a frame including a head, the combination of a stationary bearing, a presser-bar slidably mounted within said stationary bearing, a bearing pivotally carried upon said head, means to rock said last mentioned bearing about its pivot, a feed-bar slidably mounted within said rocking bearing, a swinging arm pivotally mounted upon said head, independent connections between said arm and said presser- and feed-bars, means associated

11

with said arm for imparting to said presser- and feed-bars mutually alternating lifting movements, a spring for pressing said bars upon the work, and means interposed in operative relation between said spring and each of said bars for multiplying the applied force of said spring and applying the resultant upon each bar.

16. In a sewing machine having a frame including a head, the combination of a stationary bearing fixed to said head, a presser-bar slidably mounted within said bearing, a bearing pivotally carried upon said head, means to rock said pivotal bearing, a feed-bar slidably mounted within said pivotal bearing, a swinging arm pivotally mounted upon said head, an operable connection between said arm and said feed-bar, a rocking member fulcrumed upon said arm intermediate its connection with said feed-bar and its pivot point, a connection between said presser-bar and said rocking member, means for actuating said rocking member, a spring for pressing said bars upon the work, and means connecting said spring with said arm, said last mentioned means comprising a motion-multiplying member adapted to impose upon said spring a range of movement materially longer than that of either of said bars.

17. In a sewing machine having a frame including a head and a rotary shaft journaled within said head, the combination of a yoke pivotally carried by said head, a needle-bar slidably mounted within said yoke, a bearing member carried rigidly with said yoke, a feed-bar slidably mounted within said bearing member, means actuated by said rotary shaft for rocking said yoke, a stationary bearing fixed upon said head, a presser-bar slidably mounted within said stationary bearing, a swinging arm pivotally carried by said head, connections between said arm

12

and said feed-bar, a rocking member fulcrumed upon said arm intermediate its connection with said feed-bar and its pivot point, a connection between said presser-bar and said rocking member, means operatively connected to said rotary shaft for actuating said rocking member, a spring for pressing said presser and feed-bars upon the work, and means connected with said spring for transmitting the thrust thereof upon said arm.

18. In a sewing machine having a frame including a head and a work-support, a presser mechanism including a presser-foot, a presser-bar carrying said presser-foot and slidably mounted within said head, a lever fulcrumed intermediate its ends and bearing at one end on said presser-bar, a spring connected at one end to the other end of said lever, a member connecting the other end of said spring to said frame whereby said spring is subjected to tension and through said lever adapted to normally depress said presser-bar, and means associated with said presser mechanism for damping vibrations set up in said spring, said means including a pair of fluid-tight complementary telescoped members relatively shiftable in response to movements of said tensioned spring.
